MARCUS MAZER, OF PHILADELPHIA, PENNSYLVANIA.

ACOUSTIC PANEL.

Application filed January 19, 1928. Serial No. 247,956.

The present invention relates to sound absorbing material for use particularly to wall and ceiling construction for controlling the acoustics of a room or other enclosure, and 5 has for an object to provide an improved means for supporting the material against sagging or displacement incident to the weight of the material.

Felt is recognized by acoustic engineers as 10 being a sound absorbing material of a high degree, and it is also well known that other materials, among which may be mentioned fibrous and porous substances, mineral wool and the like, possess to various degrees, the 15 sound absorbing qualities which are found in felt.

Felt, however, is a material which is more readily handled and has proven by experience to be very effective in the correction of acous- 20 tic defects.

Various attempts have been made in practice, and also in the patented art, to support the sound absorbing material in position and maintain it from sagging or shifting incident 25 to its vertical or horizontal position when either in the ceiling or in the wall, but while such prior attempts have materially aided in the support of the acoustic material, the means have not been entirely satisfactory and the 30 mounting of the acoustic material has not been of the permanent nature which is so desirable.

When the sound absorbing material sags or becomes displaced it destroys the uniform ab- 35 sorption of the sound waves and the smooth flat surface of the ceiling or wall, and thus destroys the aesthetic appearance of the room or enclosure with which the architects are greatly concerned.

40 It is another object of this invention to provide a support for the fibrous sound absorbing material, which is of a permanent nature, which may be incorporated into the structure of the material, so as to become intimately as- 45 sociated with the fibers thereof and thus uni- formly and permanently support the material in either the ceiling or the wall, and to pro- 50 vide a supporting means which may be placed either within, above or below the sound ab- sorbing material.

Another object of the invention is to pro- 55 vide a support of this nature which will not only hold the material from sagging or dis- placement, but which will also maintain the material taut and provide a support which may be easily and accurately secured in posi-

tion to hold the felt or other material used.

With the foregoing and other objects in view, the invention will be more fully described hereinafter, and will be more par- 60 ticularly pointed out in the claim appended hereto.

In the drawings, wherein like symbols refer to like or corresponding parts throughout the several views.

65 Figure 1 is a fragmentary plan view of a portion of sound absorbing material having the support embedded therein, part of the material being broken away to show the sup- 70 port.

75 Figure 2 is a fragmentary section view taken transversely through a frame or the like, showing a portion of the sound absorbing material with its support secured to the frame.

Figure 3 is a fragmentary sectional view through a portion of the sound absorbing material, showing a slight modification in the structure of the same with its support, and

80 Figure 4 is a similar view showing another modification of the mounting of the material on the support.

Referring to the drawing, and first to the structure shown in Figures 1 and 2, 10 indi- 85 cates a body of sound absorbing material which may be felt, or any other suitable sub- stance of a fibrous or sound absorbing nature and which is adapted to be placed over the ceiling or wall, or certain parts thereof, for the purpose of absorbing sound and eliminat- 90 ing or reducing reverberatory sound waves which destroy the acoustic properties of an enclosure. The body of the fibrous material 10 may be felt and in the formation of the body 10 there may be incorporated a support- 95 ing fabric 11 of relatively large open mesh wire or the like, as shown and about and through which are felted the fibers of the body 10, so that the support 11 becomes sub- 100 stantially an integral part of the sound ab- sorbing material.

The wire 11 may be coextensive with the length and width of the material, but may be cut with the material to the required size for filling in panels or the like as may be required in the construction of the walls either orig- 105 nally or as subsequently treated.

In Figure 2 a frame 12 is shown for sup- 110 porting the acoustic material, and the frame is provided with a cleat 13 which may be in the form of a brace or shoulder upon which the edge portion of the material 10 is adapt-

ed to rest. A staple 14, is driven through the material 10 and the support 11 and into the shoulder 13 so as to hold the material 10 taut. Any other suitable mounting for the sound absorbing material may be resorted to depending upon the conditions of installation, and the frame may be discarded.

As shown in Figure 3, the sound absorbing material 15 may be placed against the under 10 side of the wire mesh support 16 and held thereto by tuft wires 17, which are placed at suitable intervals throughout the material 15 and which are twisted, tied or otherwise suitably secured to the wire mesh support 16. 15 In this manner, the body of material 15 may be held in the ceiling, or in the wall with its outer free surface exposed for absorbing the vibrations set up by sound.

In Figure 4, the other modification shows 20 the wire mesh support 18 at the lower or outer face of the sound absorbing material 19. The material 19 rests by gravity against the support 18 and is thus held against sagging. The wire mesh support may be made of 25 any suitable wire of the desired weight and with a mesh of the desired size for holding the sound absorbing material flat and from

shifting or sagging. The support 18 may be coextensive with the material and may be readily cut or severed with the material, so 30 as to form a part thereof, and so that the support may be easily anchored or secured in frames or against walls or ceilings, or other grounds.

It is obvious that various changes and 35 modifications may be made in the details of construction and design of the above specifically described embodiment of this invention without departing from the spirit thereof, such changes and modifications being restricted only by the scope of the following claim:—

What is claimed is:—

A sound absorbing panel for use in wall, 40 floor and ceiling construction, comprising a frame member adapted to be supported upon said wall, floor and ceiling, a body of fibrous sound absorbing material, and a sheet of wire meshing embedded in the fibrous material and secured in said frame member to support the fibrous material in position in the frame member against stretching and sagging.

In testimony whereof I affix my signature.

MARCUS MAZER.
